UNITED STATES PATENT OFFICE.

GEORGE B. DAHL, OF BROOKLYN, NEW YORK.

OIL BURNER.

Application filed April 28, 1927. Serial No. 187,159.

My invention relates to improvements in oil burners, and the general object of my invention is to produce a simple, practical oil burner which is adapted to use a gravity feed, and which has a very wide range of capacity, so that a burner of a given size can be easily regulated so as to generate a relatively small, or a very large amount of heat.

10 The invention is, also, intended to produce a burner which will work successfully on a very low grade of fuel oil without very much carbonizing.

15 The invention is, also, intended to produce a structure embodying a vaporizer arranged to rapidly and evenly vaporize the fuel oil, and I have this vaporizer arranged so that whatever carbonization occurs, will deposit the carbon on certain parts of the vaporizer, and have this vaporizer freely removable, as by lifting from the burner, so that when carbon does collect thereon, it can be lifted from the burner and cleaned, or another vaporizer substituted for it.

20 25 My invention is further intended to produce a structure in which the admixture of oil vapor and air vapor are perfectly controlled, and to provide means for seating the parts of the burner so that the proportion of air delivered will be in proportion to the oil consumed, to the end that substantially perfect combustion may be obtained, and it is this arrangement for controlling the air draft and mixing, which gives to the 30 35 structure its very wide range of heating capacity.

The invention is further intended to produce a structure of few parts which can be readily assembled or disassembled, and in 40 which the several parts are disposed and shaped so as to produce the best combustion and the best application of the generated heat to a part to be heated, as, for example, a boiler.

45 The invention is further intended to produce a structure which can be readily applied to ordinary furnaces or the like, and from which any accumulation of sediment as, for example, when very low grade oil is used, 50 can be easily removed.

These, and other advantages, will appear more clearly from the following description.

Reference is to be had to the accompany-

ing drawings in which similar reference characters represent the corresponding parts in all views.

55 Figure 1 is a vertical cross section of a burner showing my improvements.

Figure 2 is a broken section plan on the line 2—2 of Figure 1.

60 Figure 3 is a broken horizontal section on the line 3—3 of Figure 1, and

Figure 4 is a detail bottom plan of the vaporizer.

65 The burner has, near the bottom, a central oil well or trough 10 and, by having it disposed at the bottom part of the burner, it makes it easy to collect and remove any sediment, as will hereinafter appear.

70 The well is supplied with fuel oil from a pipe 11 but the oil may be supplied to the well in any convenient way, and the upper wall of the well merges into an outwardly flaring part 12 which, in turn, assumes a cylindrical shape, as at 13, so that the parts 75 10, 12, and 13 form the bottom casing of the burner.

75 The upper edge of the part 13 has outwardly extending socket lugs 14 which rest on complementary lugs 15 extending inward from a sustaining ring 16, and this can be supported in any usual or preferred way.

80 At the base of the part 13 of the casing, is an overflow pipe 17, through which any excess of oil may pass, to prevent flooding the burner.

85 Arranged centrally within the burner, is a freely removable and unattached vaporizer 18 which forms an important part of the invention, and which can conveniently be a casting, and this vaporizer is given a substantial mass so that it will retain heat readily for the purpose of vaporizing the incoming oil, and it has its central portion extended downward as at 19, to rest in the bottom part of the well 10.

90 The vaporizer 18 has an outwardly flaring apron or deflector 20 which is curved downwardly and outwardly from the upper part of the central portion of the vaporizer, 100 and spaced around the under side of the oil deflector 20 are ribs 21 of such a contour as to rest on the wall 12 of the casing and, also, to extend downward close to the wall of the well 10.

105 These ribs stiffen the deflector 20, give

mass to the vaporizer, and serve to divide the incoming fuel into numerous streams so that it burns to better advantage.

The ribs can be recessed as at 22, at points 5 opposite the intake pipe 11, so that when the vaporizer is dropped in place, if a rib should come opposite the pipe 11, it will not offer obstruction to the inflowing oil and, furthermore, the recesses 22 act as ports to 10 permit the oil to pass to all parts of the well.

The upper side of the apron or deflector 20 is stiffened by ribs 24, and the vaporizer has, on the top surface, a socket 25 which 15 receives the reduced lower part of a refractory flame spreader 26. This, it will be seen, is located centrally of the burner, and it curves outwardly towards its upper part, as shown at 27, so that the flames rising from 20 the burner will spread around the spreader, and strike evenly and effectively upon the part above which is to be heated.

The spreader 26 has a bore 28 therethrough, and a rod 29 extends vertically 25 through this bore and is attached to the vaporizer as at 30, being screwed into the vaporizer, but it may be otherwise attached. This rod 29 has an edge 31 at the top so that 30 a poker or other instrument can be engaged in the eye, and the vaporizer lifted bodily from the burner.

It will be understood that other means can be employed for lifting the vaporizer, and that the particular arrangement of the 35 spreader and vaporizer, while desirable, is not essential, as the important things are, first, to have the vaporizer arranged as shown so that it can be lifted freely from its position in the burner, and to have a 40 spreader superposed above the vaporizer.

In the arrangement which I have shown and described, the oil will vaporize and begin to burn at the channel 23 between the oil deflector 20, and the opposite wall 12 of 45 the burner, and any deposition of carbon which occurs, will be adjacent the edge and lower side of the deflector 20.

If, in the lapse of time, carbon does occur on the vaporizer, it will be seen that it can 50 be lifted from the burner, and the carbon removed, after which the vaporizer can be replaced, or a better practice is to have two vaporizers available so that one can be replaced while another is being cleaned.

55 The burner is adapted to use a very low grade oil and, sometimes, such oil has a sediment which separates out and, to provide for removing this, the bottom of the well 10 is removable.

60 A convenient way of getting at this result, is to have the lower extension of the well screw threaded as at 32, and have a cup 33 threaded into the part 32 and provided with faceted parts 34 to facilitate screwing 65 the plug cup in or out of the socket.

Within the lower casing of the burner, and near the outer part of the wall 12, is an annular seat 35, upon which rests the tapering air deflector 36 which is in the form of a ring, having the smaller opening downward and inward, and flaring outward to a point in close connection with the wall 13. This ring projects so as to leave a fuel passage between its inner and lower edge, and the edge of the oil deflector 20 as shown, 75 and it forms one wall of the means for controlling the air supply or draft. This supply to the flame comes into the channel 37' which is located between the air deflecting ring 36 and the lower edge of the air or 80 mixing drum 37, this being well shown in Figure 1.

This drum is vertically arranged, so spaced apart from the wall 13 and ring 36 to provide for air inflow, and is spaced apart 85 from the vaporizer 18, to provide for the proper mixing and burning of gases. It will be noticed by reference to Figure 1 that by raising or lowering the air drum 37, the size of the channel 37' is changed, and by properly adjusting the height of this air drum, the air need can be cut down to correspond to a relatively small inflow of air to mingle with the corresponding increase of oil supply. 95

The regulation of the wall 37 of the air drum or mixing drum can be effected in many ways without departing from the invention. I have shown the drum flaring outward as at 38, provided with strengthening ribs 39, and with a downturned annular wall 40 resting on a corresponding wall 31 which rises from the supporting ring 16. 100

These two walls 40 and 41 are illustrated as having a cam connection 41' so that when 105 the drum 37 is turned one way or the other, it will be raised or lowered by such action.

I have not shown this in detail because it is the same arrangement, substantially, which I have illustrated in my Letters Patent of the United States 1,613,820, dated January 11, 1927, although the action, arrangement and location of the air drum is somewhat different. I have shown the air drum provided with a downwardly extending part 42 connected with a lever 43 which can be moved by any suitable means, annular or otherwise, to effect the turning of the air drum and its corresponding vertical adjustment; but, as stated, this arrangement 110 is merely one way of adjusting the air drum. 115

In practice, the oil is admitted in a regulated quantity to the well 10, the oil is ignited, the vaporizer 18 becomes hot, and, by reason of its mass and shape, serves to rapidly vaporize and assist in the distribution of the oil vapor, while the air will flow inward between the parts 13 and 16, downward between the parts 13 and 37, and inward through the channel 37' where it unites 120 125 130

with the oil vapor, rises and burns in the air drum or mixing drum 37, and the flames from the burner arise around the spreader 26 to be effectively utilized.

5 I claim:

1. An oil burner having a centrally disposed tapered oil well therein, a vaporizer coaxially seated in the well and having a downwardly and outwardly extending oil deflector, and a spreader seated coaxially on the vaporizer, and having an outwardly and upwardly curved wall.

10 2. An oil burner having a centrally disposed tapered oil well, and a removable vaporizer having an annular flared portion provided with a plurality of inclined ribs to form recesses on the underside of said vaporizer, said ribs being adapted to seat said vaporizer in said well.

15 3. An oil burner having a centrally disposed tapered oil well, and a removable vaporizer provided with a central longitudinal conical portion and an annular flared portion, said flared portion having a plurality of inclined ribs radiating from said conical portion to form recesses on the underside of said vaporizer, said ribs being adapted to seat said vaporizer in said well.

20 4. An oil burner having a centrally disposed tapered oil well, and a removable vaporizer comprising a solid portion, a plurality of ribs radiating from said central

portion, a circular deflecting apron integral with and disposed above said ribs, means forming a channel for supplying air to the 35 burner, and a deflecting ring disposed in said channel adjacent the periphery of said apron.

5. An oil burner having a centrally disposed tapered oil well, and a removable vaporizer comprising a solid central portion, a plurality of ribs radiating from said central portion to form recesses on the underside of said vaporizer, a deflecting apron integral with and disposed above said ribs, 40 the edge of said ribs being inclined to contact the wall of said well, said edges being provided with depressions to permit communication between said recesses.

6. An oil burner having a centrally disposed tapered oil well, and a removable vaporizer comprising a solid central portion, a plurality of ribs radiating from said central portion to form recesses on the underside of said vaporizer, an oil deflecting 55 apron disposed above said ribs, said apron being downwardly and outwardly curved, and a flame spread arranged coaxially on said vaporizer, said spreader being upwardly and outwardly curved.

In testimony whereof, I have signed my name to this specification this 20th day of April, 1927.

GEORGE B. DAHL.
